(74) Attorney, Agent, or Firm — The Firenza Group Ltd.;
Sharon R. Kantor(57) **CLAIM**

The ornamental design for a combined dispenser and applicator, as shown and described.

DESCRIPTION

FIG. 1 is a top left front perspective view of a combined dispenser and applicator showing my new design;

FIG. 2 is a left side view thereof;

FIG. 3 is a right side view thereof;

FIG. 4 is a front view thereof;

FIG. 5 is a rear view thereof;

FIG. 6 is a top view thereof; and,

FIG. 7 is a bottom view thereof.

The broken lines illustrating portions of the combined dispenser and applicator form no part of the claimed design.
